UNITED STATES PATENT OFFICE.

SIDNEY A. REEVE, OF WORCESTER, MASSACHUSETTS, ASSIGNOR TO CHARLES F. BROWN,
TRUSTEE, OF READING, MASSACHUSETTS.

INTERNAL-COMBUSTION POWER APPARATUS.

No. 872,452.

Specification of Letters Patent.

Patented Dec. 3, 1907.

Application filed February 7, 1906. Serial No. 299,889.

To all whom it may concern:

Be it known that I, SIDNEY A. REEVE, a citizen of the United States, residing at Worcester, in the county of Worcester and State of Massachusetts, have invented certain new and useful Improvements in Internal-Combustion Power Apparatus, of which the following specification and accompanying drawings illustrate the invention in a form which I now regard as the best out of the various forms in which it may be embodied.

This invention relates to motive apparatus for developing power from the internal combustion of fuel where the working fluids are pumped or compressed prior to their combustion by means of pumps located outside of the expansion cylinders or engines.

The principal method heretofore proposed in such apparatus is to connect the pumps directly to the main working motor, which is, therefore, obliged to furnish power for working the pumps in addition to the power supplied to its shaft for driving outside machinery, but I have found that many advantages may be derived by either wholly or partially operating the pumps from a separate source of power. Under this latter arrangement it becomes possible to effect an easy start, to operate the pumps at a higher speed than the main engine if desired and more or less independently of the speed of the main engine, thereby enabling the pumps and their motor if desired to be made in smaller dimensions because of their higher speed, besides eliminating some difficult problems encountered in so designing the whole apparatus as to minimize machine friction.

The invention also includes an arrangement of internal combustion power apparatus to operate at a high pressure which involves the compression and expansion of the elastic fluid in stages and it further includes the arrangement of the compressing motor or motors in certain novel combinations with the devices for burning fuel and generating steam by contact with water of the products of combustion.

Of the accompanying drawings, Figure 1 represents a diagrammatic elevation of a power apparatus constructed according to my invention. Fig. 2 represents a detail dia-

grammatic section of one of the gas-compressors.

55

1 represents a compound engine of the steam-engine type having a high-pressure cylinder 2, a low-pressure cylinder 3 and an intermediate receiver 4, through which the working mixture passes and is subjected to successive expansions while doing work. This engine is connected to drive the pistons of a gas-compressor cylinder 5 and an air-compressor cylinder 6, which are the high-stage members of the compressing department.

7 7 are the low-stage air-compressors, receiving atmospheric air through an inlet 8 and discharging the compressed air to the high-pressure compressor 6 through a conduit 9 containing an intercooler 10. 11 11 are the low-stage gas-compressors, receiving gas from a main 12 and discharging the compressed gas to the high-pressure compressor 5 through a conduit 13 containing an intercooler 14. The pistons of these compressors 7 and 11 are single-acting and attached to two oppositely-moving piston-structures shown in dotted lines and connected by a rocking beam 15, which has a pitman-connection with a fly-wheel 16.

70

The upper ends of the moving piston-structures are the pistons of a pair of intermittent-combustion motors 17, preferably explosive motors. These may have the general construction, including valves and igniters, of the ordinary Clerk or two-cycle engine, which performs a preliminary compression in its working cylinder on the back stroke of the piston, explodes and expands the charge on the next out-stroke, exhausts the exploded charge by the opening of an exhaust-port at the end of the working stroke, and during the same period admits the next working charge while the exhaust-port is open. These arrangements being well known are not fully illustrated, as they are merely the preferred arrangement of the separate compressing motor and might be varied if desired. In certain important respects however, the manner of operation of these motors 17 differ from the ordinary two-cycle explosive engine.

75

The charge for the cylinders 17 is received from the low-pressure cylinders 7 and 11 by means of pipes 18 19 containing intercoolers

37 38, and thus it will be seen that this charge before explosion, if the motors 17 are of the compression type, receives a two-stage compression, the first stage being 5 performed by the air and gas compressors 7 11 and the second stage performed after mixing of the charge in the cylinders of said motors 17. In order to avoid loss of the low-pressure compression work, this arrangement 10 calls for a further stage of expansion of the burned charge after it leaves the motors 17, and accordingly I carry the exhaust of these motors through a pipe 20, generator 21 and a pipe 22 into the receiver 4 of the main 15 motor 1 to be expanded in the low-pressure cylinder 3 of the main motor. The products of combustion pass downwardly through a pipe 23 in the generator 21 into a pool of water contained in a water-pot 24 in the lower part 20 of the generator, where they impart their high-temperature heat to the water and create a body of steam which passes upwardly around the outside of the tube 23 together with the products of combustion, and the 25 mixture passes outwardly through the pipe 22. A substantially constant supply of water is maintained in the water-pot through a pipe 25 under suitable automatic control.

Generator 21 is preferably of the general 30 type shown in my Patent No. 588,293 and as thus constructed includes a constant pressure burner 26. It further includes an automatic regulating device 27 of any suitable character for controlling the compressed 35 air and gas which are fed to the burner from the low-pressure compressors 7, 11 through pipes 28 29. I thus impart to the generator 21 a double function which I believe to be new, viz: that of a cooling chamber 40 for the exhaust gases of the explosion motors 17, and also that of a combined burner and cooling chamber for compressed fluids burned at constant pressure. The products of combustion from burner 26 pass downwardly 45 through the tube 23 and are quenched in the body of water in the water-pot 24 so that the pipe 22 receives steam from one source and products of combustion from two sources.

50 The general arrangement of an explosion motor, and a low-pressure motor cylinder substantially in the manner described but without plural combustion and other specific features covered by the present claims, 55 is made the subject of my copending applications Ser. Nos. 267,718, 267,719, and 349,019.

Compressed air and gas from the high-stage compressors 6 5 pass through pipes 60 30 31 and a generator 32 similar to the generator 21, being burned at constant pressure and the mixture of products of combustion and steam passing out through a pipe 33 to the high-pressure cylinder 2 of the main 65 motor 1 and being expanded in two stages

therein. The generator 32 operates at the maximum pressure of the system furnished by the high-stage compressors 6 5, while generator 21 operates at the pressure furnished by the low-pressure compressors 7 11. 70

34 is a diaphragm device operating a throttle-valve 35 in the suction gas-conduit 12 and including a diaphragm which receives through a pipe 36 the pressure from air-inter-cooler 10 balanced against a suitable constant pressure such as atmosphere and a spring, whereby the relative amount of fuel may be regulated so as to maintain inter-cooler pressure substantially constant. 75

In starting the apparatus when no fluids are under compression the motors 17 will first operate as ordinary two-cycle explosive motors from and at atmospheric pressure, drawing uncompressed fluids from the inter-coolers 37 38. Pressures soon begin to accumulate and permit a back pressure during the exhaust period of the motors 17. Then a constant-pressure flame may be started in the generator 21 and the motor 1 may be started on its low-pressure cylinder. As soon as sufficient high-pressure fluids have been accumulated the flame of the generator 32 may be started and the apparatus will then be in full operation. The action of the burner 26 is not essential to a start however, and if preferred the generator 21 may be run without flame, its output of steam, hot gases from engines 17, and surplus air, if any, from compressors 7, going to the low-pressure engine 3. With this pressure fluid as a motive power, engine 3 may be started and the constant-pressure burner of generator 32 set in operation, only in that case the water in pot 24 is preferably already hot and burner 26 is a convenient means for getting it so. Furthermore, burner 26, and especially its excess air, furnishes a means for consuming any unburned charges which may come over from the explosion-engines 17. 90 95 100 105

Fig. 2 shows diagrammatically, an arrangement for the gas-compressor outlets, whereby, although feeding several receptacles, this compressor will meter proper quantities of combustible to the explosion cylinders. The outlet ports 39, 40 to the high-pressure cylinder 5 and burner 26 respectively are successively covered by the piston 41 in its compressing stroke, while the outlet port 42 to the explosion engines 17 is not covered. The springs to the several check-valves governing these ports are adjusted so that the ports 39, 40 and 42 open in succession. A similar arrangement is adopted for the air compressors. Various equivalent devices might be substituted to accomplish the same result, and in the present application I claim only the combination of this distributive device with a plurality of internal-combustion motors or with one such motor and a high-stage compressor, the more gen- 110 115 120 125 130

eral aspects of the device being treated in a separate application, Serial No. 322,204.

I have further shown stop-valves 43, 44 in the conduits 9, 13, speed-controlled by a suitable shaft-governor, whereby these conduits are choked down when the speed rises unduly and the pressure-reaction on the regulator 34 serves to diminish the power of the compressing engines 17.

10 Various modifications may be made within the scope of the invention. For example, while I consider it desirable to operate the high-stage compressors 5, 6 from the main motor 1 in order to balance the work of this 15 motor, it is not essential that they should be so operated, as both high and low stage compressors may be operated by the motors 17. Also the internal-combustion unit comprised by motor 1 and generator 32 may in a broad 20 sense be varied and replaced with an equivalent either of a different type or a variation of the constant-pressure type without departing from my invention.

What I claim as new and desire to secure 25 by Letters Patent is:

1. A power apparatus comprising a main motor, a constant-pressure internal-combustion burner for supplying motive fluid thereto, a charge-compressor for supplying said 30 burner, and an independently-running internal-combustion motor driving said charge-compressor and supplied with motive fluid from said charge-compressor independently of said burner.

35 2. A power system comprising a main motor having an internal-combustion burner for supplying it with motive fluid, a mechanically-separate intermittent-combustion compressing motor, and a charge-compressor operated by the last-said motor and supplying compressed fluid for both motors.

3. A power apparatus comprising a main motor operated by internal combustion of compressed air and fuel, a compressor for 45 supplying the charge to said main motor, and an explosion motor for driving said compressor, adapted to operate with a charge compressed by said compressor.

4. A power system comprising high and 50 low stage serial charge compressors, and two independently-running motors, both operated by the internal combustion of the compressed charge, one of said motors operating the high-stage compressor and the other operating the low-stage compressor.

5. A power system comprising high-stage and low-stage compressors, a motor operated by continuous internal combustion of compressed charge and driving one of said compressors, and a motor operated by internal combustion of compressed charge and operating the other compressor.

6. A power system comprising a main motor, a constant-pressure internal-combustion 65 burner supplying the motive fluid, an inter-

mittent internal-combustion motor, and means for supplying compressed charge to the burner and the intermittent-combustion motor, said means including a low-stage charge-compressor driven by the intermittent-combustion motor, and a high-stage charge-compressor driven by the main motor.

7. A power system comprising high and low stage serial charge-compressors, an internal-combustion motor driving one of said 75 compressors and operated by the combustion of the high-stage compressed fluid, and a second internal-combustion motor driving the other compressor and operated by the combustion of charge abstracted from between the stages of compression.

8. A power system comprising a main motor, a constant-pressure internal-combustion burner supplying the same, a high-stage charge-compressor operated by the main motor and supplying said burner, a low-stage charge-compressor, and an intermittent-combustion motor driving said low-stage compressor and supplied by compressed charge from between the high-stage and low-stage compressors.

9. A power system comprising a plural-stage expansion motor operated by internal combustion of compressed fluid, a charge-compressor to supply the same, and an intermittent internal-combustion motor driving said compressor and exhausting into the first-said motor between the stages of expansion thereof.

10. A power system comprising high and 100 low stage charge-compressors, a constant-pressure motor driving one of said compressors, and an intermittent internal-combustion motor driving the other compressor, the last-said motor being supplied with compressed charge from between the said compressors and exhausting into the first-said motor.

11. A power system comprising a serial-stage expansion motor having an internal-combustion burner, an intermittent internal-combustion motor exhausting into the first-said motor between the stages thereof, and means for supplying compressed charge to said burner and motor, including a compressor driven by the intermittent-combustion motor.

12. A power system comprising a plural-stage expansion motor, and two generators connected respectively to the higher stage 120 and between the stages of said motor and each having a passage for gases of combustion leading to the motor and means for quenching said gases of combustion with water.

13. A power system comprising a plural-stage expansion motor, two generators connected respectively to the higher stage and between the stages of said motor and having means for quenching products of combustion 130

with water, a continuous internal-combustion burner in one of said generators, and an intermittent internal-combustion motor connected to supply combustion gases to the other generator.

14. A power apparatus comprising a plural-stage expansion motor, high-pressure and low-pressure generators connected respectively to the higher stage and between the stages of said motor and each having means for quenching products of combustion with water, a constant-pressure burner in the high pressure generator, stage charge-compressing means whose higher stage supplies said burner, and an explosive compressing motor supplied by said compressing means and driving one of the stages thereof, said motor exhausting into the low-pressure generator.

15. A power apparatus comprising a motor, a generator for supplying the same and having means for quenching products of combustion with water, an internal-combustion constant-pressure burner in said generator, and an intermittent internal-combustion motor supplying hot gases of combustion to said generator.

16. A power apparatus comprising an intermittent internal-combustion motor, an internal-combustion constant-pressure burner, a water-pot adapted to maintain a pool of water in the path of the products of combustion from said burner and from said motor, and a second motor operated by the pressure of the mixture of steam and products of combustion issuing from said water-pot.

17. A power apparatus comprising an internal-combustion motor, and a compressor

driven by and supplying charge for said motor and for a burner, and having outlets to the two destinations, and means whereby said outlets are opened in succession on the compressing stroke of said compressor.

18. A power apparatus comprising serial charge-compressors, a motor supplied thereby for driving the high-stage compressor, a motor for driving the low-stage compressor, means controlled by the pressure of output from the low-stage compressor for varying the power of the motor which drives it, and means controlled by the speed of the high-stage motor for varying the intake of the high-stage compressor.

19. A power apparatus comprising high- and low-pressure charge compressors, an explosion engine charged by the low-pressure compressor, a chamber receiving the exhaust of the engine, outlets leading from the low-pressure compressor to the high-pressure compressor and to said chamber, another outlet leading from the low-pressure compressor to the explosion engine, and means whereby the last-said outlet is opened after the first-said outlets have been closed during the compression period of the low-pressure compressor.

In testimony whereof I have hereunto set my hand in the presence of two subscribing witnesses, the nineteenth day of January, 1906.

SIDNEY A. REEVE.
